CODED TRACK CIRCUIT SIGNALING
SYSTEMNeil D. Preston, Rochester, N. Y., assignor to
General Railway Signal Company, Rochester,
N. Y.Original application November 9, 1940, Serial No.
365,065. Divided and this application Febru-
ary 22, 1944, Serial No. 523,460

6 Claims. (Cl. 246—38)

This invention relates to coded track circuits for railroads, and more particularly to the transmission of inverse or off-codes for detection of the presence of approaching trains for governing the approach lighting of signals and the like.

This application is a division of my prior application, Ser. No. 365,065, filed November 9, 1940, for a Coded track circuit signaling system.

In the usual arrangement of a coded track circuit employing inverse or off-codes, the track relay responding to the inverse code pulses is intermittently connected to the track rails by a code transmitter relay or equivalent means; and if a stray current of the proper polarity and intensity to operate this track relay should exist, then this track relay is intermittently energized, regardless of the existence of the inverse code pulses, due to the fact that this relay is intermittently connected to the sustained potential across the track rails and thus picks up and drops as the transmitter relay operates. Such false self-coding may be prevented, as disclosed and claimed in my prior application, Ser. No. 365,065, above mentioned, by rendering the transmitter relay ineffective while the off-code track relay is energized, so that when a stray current exists operation of this transmitter relay is automatically stopped, and no longer acts to connect the track relay intermittently to the track rails and cause the objectionable self-coding operation.

One characteristic of this arrangement for protecting against improper operation by stray currents is that the off-code pulse must cease and the off-code track relay release before the transmitter relay may be energized for the next driven code pulse; and since this should occur for the higher code rates, as well as the lower code rates, it is desirable to employ a relatively short off-code pulse. When the duration of the off-code pulse is thus selected, the periods of energization and deenergization of the off-code track relay are unequal, more particularly at the low code rates. The energization and deenergization of a track relay at uniform intervals, however, is desirable for more efficient and uniform control of the de-coding means, particularly the type using an impulse de-coding transformer.

In view of these considerations, it is proposed in accordance with this invention to provide means for artificially prolonging the operation effect of an off-code pulse to provide contact operation substantially in accordance with the code rate, and thus obtain more efficient operation of a code responsive means.

Generally speaking, and without attempting to define the exact nature and scope of the invention, it is proposed to provide a repeater relay for the off-code track relay which is governed by this track relay and the coding contacts providing the driven code pulses in such a way that this repeater relay, after each operation thereof in response to the energization of the track relay, remains in such operated condition, independently of the deenergization of said track relay upon cessation of the off-code pulse, until the coding contacts again operate to provide a driven code pulse. In this way, while the off-code track relay follows the inverse code pulses and may be used to provide the desired control for protection against false self-coding in the presence of stray current, the repeater track relay is energized and deenergized at substantially equal intervals in correspondence with the driven code rate then in effect.

In one embodiment of the invention, this repeater relay is of the two-position magnetic stick type and has its armature or contact element operated back and forth in response to the energization of the track relay and closure of the coding contacts respectively. In another embodiment of the invention, the repeater relay is a neutral relay maintained energized after each energization thereof in response to the operation of the track relay by a stick circuit opened upon closure of the code contacts to provide the next driven code pulse.

Various other characteristic features and attributes of the invention will be in part apparent and in part pointed out as the description progresses.

The accompanying drawing illustrates in a simplified and diagrammatic manner certain specific embodiments of the invention, the nature of the illustration being intended to facilitate an understanding of the structural organization and mode of operation of the invention, rather than to show the particular arrangement and detailed construction of the parts preferably employed in practice. In the drawing—

Fig. 1 illustrates a typical organization for providing inverse or off-code impulses for a track section, together with one embodiment of the invention for providing uniform relay operation for the control of code responsive means; and

Fig. 2 illustrates another embodiment of the invention for the same purpose.

It is assumed that the coded track circuit will be of the conventional direct current type, and that the signal controlling or driven codes at the

desired different rates, such as 75 and 180 on and off periods per minute, will be obtained from a suitable coding device or transmitter having contacts designated C180 and C75 intermittently opened and closed at the desired code rate in the usual manner. Referring to Fig. 1, it is assumed that the driven code pulses from right to left in the track section shown, as indicated by the solid arrow, will be employed for governing the indications of a way-side signal I at the entrance to such track section, and that the inverse or off-code pulses in the opposite direction, as indicated by the dotted arrow, will be employed to govern the energization of a relay OCH to provide approach lighting for some other signal not shown, control of approach locking for a power operated track switch, or for some like purpose. The selection of the code rates to be effective at any given time for governing the indications of signal I may be determined in any suitable manner, and the relay X is typical or illustrative of means suitable for this purpose. Also, as illustrated in Fig. 1, it is assumed that the inverse or off-code will be controlled by the presence of a train in one or more adjoining track sections, due to the occupancy of some other coded track circuit or the like; and the relay Y is typical or illustrative of such a means for cutting off the inverse code prior to and independently of the entrance of a train into the track section shown.

Considering the particular form of the invention shown in Fig. 1, a transmitter relay CP is intermittently energized by the closure of coding contacts C180 or C75 as selected by the contact 9 of the relay X; and this transmitter relay CP operates a contact finger 4 to connect alternately across the track rails 2 of the track section shown, a track battery 5 in series with a suitable limiting resistance 6, and an off-code track relay OCTR, as said transmitter relay CP is energized and de-energized respectively. The off-code track relay OCTR is preferably of the two-position biased polar type, and operates a contact finger from the biased position shown by a solid line to the other operated position shown by a dotted line when this relay is energized by an inverse code pulse.

A significant characteristic of this invention is that the energizing circuit for the transmitter relay CP includes the contact finger 40 of the track relay OCTR in the deenergized biased position, so as to provide the desired protection against improper self-coding in the presence of stray current. This circuit for the energization of the relay CP in the arrangement of Fig. 1 may be readily traced from (+), back contact 40 of relay OCTR, through coding contacts C180 or C75 and front or back contacts 9 of relay X, as the case may be, through the transmitter relay CP, to (-).

The equipment at the other end of the track section for de-coding the driven codes and transmitting inverse code pulses may be of any suitable form in accordance with regular practice. In the arrangement illustrated in Fig. 1, an impulse relay IMP of the two-position biased polar type is arranged to act, when it is deenergized and its contact finger 10 is moved to the biased or left-hand solid line position, to connect a code following track relay CFTR across the track rails 2. When the relay IMP is energized as presently explained, and its contact finger 10 is moved to the right-hand or dotted position, a suitable battery 11 is connected across the track rails to provide the desired inverse or off-code pulse, the ener-

gization of the relay IMP being of limited duration so that this inverse code pulse is relatively short.

The code following track relay CFTR operates suitable de-coding means for governing the indications of signal I in the usual manner. As illustrated, the contact finger 12 of the relay CFTR energizes alternately the two halves of the primary of a de-coding transformer 13 having the usual mid-tap connection. One secondary of this transformer 13 is connected through rectifying contacts 14 on the relay CFTR to the home relay 1H. Another secondary of the de-coding transformer 13 energizes a circuit including a condenser 29 and tuned for the 180 code rate for impelling the primary of a transformer 16 having its secondary connected through a full-wave rectifier 17 to a distant relay 1D. The home relay 1H and the distant relay 1D govern the green, yellow and red indications of the signal I in the usual manner.

Considering the arrangement shown for providing inverse code pulses, an impulse winding 18 on the de-coding transformer 13 acts to energize temporarily the impulse relay IMP when the code following track relay CFTR is deenergized at the end of each "on" period of the driven code. This impulse winding 18 is so wound and connected to the relay IMP that the momentary voltage induced in said winding when the relay CFTR drops sends current through the relay IMP in a direction to move its contact finger 10 from the biased position, while the voltage induced in the impulse winding 18 when the relay CFTR picks up is in a direction to hold the relay IMP in its biased position. If as assumed the inverse code is to be controlled by occupancy of one or more track sections in the rear, the circuit for the impulse relay IMP includes a front contact 19 of the relay Y exemplifying such control.

The inverse code is employed in accordance with this invention to maintain energized suitable code responsive means associated with the transmitting or exit end of the track section, and for satisfactory and efficient operation of such a code responsive means, it is desirable to have contacts operated at substantially uniform intervals. Since the transmitter relay CP in this invention cannot be energized upon closure of the coding contacts until the off-code track relay OCTR is deenergized, it can be appreciated that prolongation of the inverse code pulse tends to artificially prolong the "off" periods of the driven code and shorten the "on" periods. It is contemplated that quick acting relays will be used, and the system otherwise so organized that the normal inverse code pulses will fit in the normal "off" period of the driven codes at the highest code rates, with a suitable margin to take care of varying ballast resistances and battery voltages. Under these conditions, it can be seen that the period of energization of the "off" code track relay OCTR is likely to be much shorter than the period of de-energization, particularly at the low code rates. Accordingly, it is desirable to prolong artificially the response to an inverse code to conform with the code rate in effect, while at the same time permitting the off code track relay to follow the code and permit energization of the transmitter relay CP.

In the arrangement shown in Fig. 1 for this purpose, a repeater relay TP of the two-position polar magnetic stick type is employed to maintain a slow release relay OCH energized in response to the intermittent operation of track

relay OCTR by inverse code pulses. As illustrated, the contact finger 20 of relay TP in its different operated positions energizes the two halves of a de-coding transformer 21, the secondary of which is connected through a rectifying contact 22 on relay TP to the slow release relay OCH.

In this arrangement of Fig. 1, when the off code track relay OCTR is energized by an inverse code pulse to move its contact finger 40 to the operated or dotted line position, one winding of the repeater relay TP is energized by an obvious circuit to shift the contact fingers 20 and 22 of this relay to one position, say to the right, as indicated by the arrow associated with this winding. The repeater relay TP, being of the magnetic stick type, remains in this position independently of the deenergization of the track relay OCTR by cessation of the inverse code pulse and until the other winding of this repeater relay TP is energized. When the coding contact C180 or C75, as the case may be, closes for the next "on" period of the driven code, and assuming the track relay OCTR is in the deenergized position, the upper winding of the repeater relay TP is energized in multiple with the transmitter relay CP by an obvious circuit including wire 23, thereby operating the contact fingers 20 and 22 of this repeater relay TP to the other position.

It can be seen that in this arrangement of Fig. 1 the two-position magnetic stick repeater relay TP is operated to one position in response to the reception of an inverse code pulse, and to the other position at the beginning of the next "on" period of the driven code pulse, thereby giving a more uniform operation of the contacts of this repeater relay for operation of code responsive means independently of the duration of the inverse code pulses.

Fig. 2 illustrates a modified organization, in which the coding contacts C180 and C75 are provided with what may be termed back contacts 24 and 25, which are closed in the left-hand position as shown during the "off" intervals of driven code transmission, as well as the regular contacts closed in the right-hand position for energization of the transmitter relay CP. The repeater relay OCTP is a neutral or polar relay having its contacts biased to a deenergized position. The upper winding of this relay OCTP is energized by an obvious circuit when the track relay OCTR is energized by inverse code pulse to move its contact 40 to the right-hand position. The lower winding of the relay OCTP is included in a stick circuit including a front contact 44 of this relay and the back contacts 24 or 25 of the coding contacts C180 and C75 dependent upon the condition of relay X.

Considering the operation of this modification in Fig. 2, assuming relay X energized and the track relay OCTR to be deenergized and the regular coding contacts open as shown, the next time the coding contacts shift the transmitter relay CP is energized by a circuit readily traced from (+), through front contact 9 of relay X, coding contact C180 in the right-hand position, relay CP, contact finger 40 of relay OCTR, to (-). This energization of the relay CP causes the application of a driven code pulse in the regular way, and during the next "off" interval, the back contact 24 of the coding contacts C180 is closed, and when the repeater relay OCTP is energized in response to the energization of the track relay OCTR by an inverse code pulse, the stick circuit through the front contact 44 and the

lower winding of the repeater relay OCTP is prepared, so that this repeater relay is held up by its stick circuit until the back contacts of the coding contacts open at the beginning of the next "off" period. This repeater relay OCTP may operate contacts 45 and 46 to control the energization of a slow release relay OCH through a de-coding transformer 21 in the same manner shown and described for Fig. 1.

It should be understood that the specific embodiments of the invention shown and described are merely illustrative of the organization and functions characterizing the invention, and that various adaptations and modifications may be made in the particular constructions and arrangement of parts and circuits illustrated without departing from the invention.

What I claim is:

1. In a coded track circuit for railroads, a track section, a source of current, an off-code track relay, a transmitter relay for intermittently connecting said source of current and said track relay alternately across the track rails of said track section at one end, intermittently operated coding contacts for operating said transmitter relay at a selected code rate, means associated with the other end of said track section for applying code pulses of limited duration during the "off" intervals of said driven code, code responsive means including a repeater relay operated by the energization of said track relay by off-code pulses, said code responsive means also including control circuits energized by operation of said repeater relay to its different conditions, and means for operating said repeater relay from one condition in response to the energization of said track relay and for restoring said repeater relay to said one condition only when said transmitter relay is again operated for the next driven code pulse, whereby the control circuits for said code responsive means are energized by said repeater relay at intervals corresponding substantially with the driven code rate in spite of the relatively short duration of the off-code pulses and energization of said off-code track relay.
2. In a code track circuit for railroads, a track section, a source of current, an off-code track relay, a transmitter relay for intermittently connecting said source of current and said track relay alternately across the track rails of said track section at one end, intermittently operated coding contacts for closing an energizing circuit for said transmitter relay, said energizing circuit being closed only if said off-code track relay is then deenergized, means associated with the other end of said track section for at times providing off-code pulses for energizing said off-code track relay, a repeater relay operated in response to the energization of said off-code track relay and remaining in such operated condition independently of the condition of said track relay until the next operation of said transmitter relay, and code responsive means governed by the operation of said repeater relay.
3. In a coded track circuit for railroads, a track section, a source of current, an off-code track relay, code transmitting means for intermittently connecting said source of current and said track relay alternately across the track rails of said track section at one end at a selected code rate, means associated with the other end of said track section for applying inverse code pulses to said track rails during the off interval between the driven code pulses for the energization of said track relay, a two-position repeater relay of the

magnetic stick type, means for operating said repeater relay to one position in response to the energization of said track relay, means for operating said repeater relay to the other position in response to the operation of said code transmitting means, and code responsive means governed by circuits including contacts closed in the different operated positions of said repeater relay.

4. In a coded track circuit for railroads, code transmitting means for alternately connecting a source of current and a track relay across the track rails of a track section at one end in accordance with a selected code rate to provide driven code pulses separated by off intervals, means for providing inverse code pulses at the other end of said track section for the energization of said track relay during said off intervals between the driven code pulses, a repeater relay of the magnetic stick type having two windings acting when respectively energized to operate the contact element of that relay to different positions, means for energizing one of said windings in response to the energization of said track relay, means for energizing the other of said windings when said code transmitting means is operated, and code responsive means including a slow release relay maintained energized by the continued intermittent operation of the contact element of said repeater relay to its different positions alternately.

5. In a coded track circuit of the character described operating to send inverse code pulses in one direction over the track rails of a track section during the off intervals between driven code

pulses over said track rails in the opposite direction, the combination with a track relay responsive to said inverse code pulses, and a transmitter relay for intermittently connecting said track relay to said track section at a selected code rate, a two-position repeater relay of the magnetic stick type operated to one position by energization of said track relay and to the other position by operation of said transmitter relay, code responsive means governed by circuits including contacts of said repeater relay closed in its different operated positions, and means for preventing operation of said transmitter relay while said track relay is energized.

10 6. In a code track circuit for railroads, a transmitter relay for alternately connecting a source of current and a track relay across the track rails of a track section at one end, intermittently operated coding contacts, an energizing circuit for said transmitter relay governed by said coding contacts and closed only if said track relay is then deenergized, a repeater relay energized in response to the energization of said track relay, means governed by said coding contacts for maintaining said repeater relay in its energized condition after each operation thereof independently of the condition of said track relay until said coding contacts operate for the next driven code pulse, and code responsive means including a slow release relay maintained energized by the continued intermittent energization and deenergization of said repeater relay.

NEIL D. PRESTON.
